ELECTROCARDIOGRAM AND HEART RATE MONITOR

Thomas P. Harper, Decatur, Ala., assignor to
Care Electronics, Inc.

Filed Dec. 22, 1969, Ser. No. 20,595

Term of patent 14 years

Int. Cl. D24—02

U.S. Cl. D83—1

FIG. 1

FIG. 2

FIG. 3

FIG. 4

FIG. 5

FIG. 1 is a front perspective view of an electrocardiogram and heart rate monitor showing my new design;

FIG. 2 is a front elevation view of my design;

FIG. 3 is a side elevation view of the left side of my new design;

FIG. 4 is a side elevation view of the right side of my new design; and

FIG. 5 is a rear elevation view of my new design.

The broken lines are shown for illustrative purposes only and do not form part of the claimed design.

I claim:

The ornamental design for an electrocardiogram and heart rate monitor, substantially as shown and described.
